BOW FACING OAR

Sion H. Williams, Hornbeak, Tenn.

Application August 30, 1933, Serial No. 687,435.

1 Claim. (Cl. 9—25)

My invention relates to improvements in bow facing oars and the main object is to provide an oar assembly in a simple and efficient form by the use of which a person rowing a boat may 5 face forwardly therein in the direction traveled.

Another object is to provide an assembly of 10 this kind including carriers mounted on the gunwales of the boat and arms pivotally mounted thereon and connected together and carrying the handles and oars, all of the pivotal connections being adjustable so as to take up for wear and prevent rattling and noise which, when the boat is used for hunting or fishing, would scare off the game.

15 Another object is to provide a structure of this kind which may be readily attached to and used on any small boat.

With the foregoing and other objects in view the invention resides in the novel construction 20 and arrangement of parts as hereinafter set forth and claimed, reference being had to the accompanying drawing wherein:

Figure 1 is a plan view of my improved oar structure as arranged on one gunwale of a boat.

25 Figure 2 is a side elevation of the pivotally mounted carrier and its supporting elements alone.

Figure 3 is an enlarged side elevation of one 30 of the oar carrying arms and an end of one of the oars.

Figure 4 is a section along the line 4—4 in Figure 3.

Figure 5 is an enlarged longitudinal sectional view through the adjustable carrier supporting 35 element.

Figure 6 is an enlarged section along the line 6—6 in Figure 1.

Referring now with more particularity to the 40 drawing my invention comprises a carrier 1 in the form of an elongated bar 2 reduced intermediate its ends and channeled out for lightness and having its ends 3 bent downward and provided with axially aligned bearing cones or points 4. This carrier 1 is pivotally supported on the 45 gunwale A of the boat (not shown) suitably adjacent the rower's seat by means of a fixed bearing 5 and adjustable bearing 6. Said fixed bearing 5 includes a base 7 apertured to receive mounting screws 8 and an upstanding head 9 having a tapered socket 10 to receive one of the bearing cones 4 of the carrier. The adjustable bearing 6 likewise includes a base 11 secured by screws 12 to the gunwale A and bearing spaced upstanding ears 13 and 14 one of which is tapped 50 at 15 to threadedly receive and engage the

threaded stem 16 which has an enlarged head 17 at one end provided with a tapered socket 18 to receive the other bearing cone 4 of the carrier 1. A lock nut 19 is threaded on the stem 16 between ears 13 and 14 and the stem may be turned through the ear 13 and adjusted and locked by the nut 19 to bring the socket 18 into proper engagement with the cone 4 and pivotally support the carrier 1 at its ends between the said bearings as will be readily understood. The stem 16 extends 10 through an aperture 20 in the ear 14 to give an additional bearing for the stem and both the head 17 and lock nut 19 are grooved or serrated as at 21 to facilitate their manual operation without the aid of tools and to make it readily possible for the 15 oarsman to adjust these elements and compensate for wear in the cones. The cones 4 have oil grooves 22 in one side by which oil is carried into their sockets.

The carrier has bearing sockets 23 and 24 near 20 its downwardly bent ends 3 which sockets taper downwardly from their open upper ends to their lower ends which are closed except for concentrically located bolt apertures 25 and 26 as shown.

A handle mounting or carrying arm 27 is provided including a tang portion 28 having a hollow rounded upper face 29 to receive the round end portion of a handle 30 which is secured thereto by bolts 31. At substantially a medial point the arm 27 has a downwardly extended and tapered bearing cone 32 adapted to enter the bearing socket 23 at one end of the carrier 1 as shown in Figure 6. This cone 32 is of such diameter, taper and length as to fall considerably short of the bottom or lower end of the socket 23 when it is 35 wedged loosely therein as shown, whereby wear on these parts may be taken up and looseness avoided by simply moving the cone down into the socket as will be readily apparent. The cone 32 has an axially extended bore 33 open clear 40 through to receive a bolt 34 which is passed down through the bolt aperture 25 and provided with a lock washer 35 and nut 36 to hold the parts together and take up the wear as described, the head 37 of said bolt being preferably sunk into a 45 recess 38 in the arm as shown so as to clear the handle end 30. The cone 32 has a peripheral oil groove 39 and upwardly extended groove 40 to facilitate oiling the cone and socket as will be 50 apparent.

At its end remote from the handle 30 the arm 27 is bent and curved laterally as at 41 and has a tapered bearing socket 42 thus offset from the axis of the arm and adapted to receive a tapered bearing cone 43 at one end of an elongated con- 55

necting bar or link 44 which is held in place by a bolt 45. At its other end this connecting bar 44 has another and similar tapered bearing cone 46 pivotally mounted in a tapered bearing socket 47 provided in one end of an oar carrying arm 48 and held therein by a bolt 49, both these pivotal connections of the ends of the bar 44 being identical to that fully described between the arm 27 and the carrier 1 as will be understood. About 10 midway of its length the arm 28 has a tapered depending bearing cone 50 mounted in the socket 24 and held therein by a bolt 51 substantially as described for the arm 27 and this arm 48 likewise includes a tang 52 having a rounded hollow 15 upper face 53 to receive the rounded end 54 of the oar 55 which is secured thereto by bolts 56.

In operation as the handle 30 is pulled back in the direction of the arrow in Figure 1 it turns in the bearing socket 23 and through the connecting bar 44 swings the oar 55 rearwardly at its outer end in the socket 24. Thus the desired rearward movement of the oar is accomplished by a person facing forward and pulling the handle back toward him. On the forward stroke of the 25 handle and oar the oar may be raised from the water by turning or tipping the carrier 1 in its bearings 5 and 6 and it will thus be understood that all the usual motions of rowing may be performed with my apparatus but with the rower 30 facing in the direction in which the boat travels. Of course a similar assembly is provided on both sides of the boat. An important feature of my construction is the tapered bearings at all points and the ease with which wear may be taken up 35 and looseness and noise prevented. Besides causing additional and rapid wear such looseness would be objectionable where the boat is used in

hunting or fishing as the noise would scare away the game. Further details of the utility and advantages of my invention will be readily understood by those skilled in the art without further description at this point.

5 While I have herein set forth a certain preferred embodiment of my invention it is understood that I may vary from the same in minor structural details so as best to construct a practical device for the purposes intended, not departing from the spirit of the invention and within the scope of the appended claim.

10 I claim:

15 In a device of the kind described an elongated carrier bar having at its ends offset and aligned bearing cones, a fixed bearing having a conical socket to receive one of the bearing cones, an adjustable bearing having a conical socket to receive the other bearing cone, the said carrier bar having conical sockets adjacent each end 20 thereof, a handle arm having a bearing cone rotatably seated in one of the sockets of the carrier bar and having a conical socket at its inner end, a handle secured to the inner end of the handle arm, an oar arm having a bearing cone 25 rotatably seated in the other socket of the carrier bar, and having a conical socket at its outer end, an oar secured to the outer end of the oar arm, a connecting bar having at its ends, bearing cones rotatably seated in the sockets at the inner end 30 of the handle arm and the outer end of the oar arm respectively, and take-up means for rotatably anchoring the several bearing cones within their respective sockets, whereby wear of the joints of the assembly may be taken up and rattle 35 of parts eliminated.

SION H. WILLIAMS.
